Primary Examiner — John Windmuller*Assistant Examiner* — Steven J Czyz(74) *Attorney, Agent, or Firm* — Smith & Hopen, P.A.; Paul Murty(57) **CLAIM**

The ornamental design for a clamping tool, as shown and described.

DESCRIPTION

FIG. 1 is a side perspective view of a clamping tool.

FIG. 2 is a side elevation view thereof.

FIG. 3 is a side elevation thereof.

FIG. 4 is a top plan view thereof.

FIG. 5 is a bottom plan view thereof.

FIG. 6 is a rear elevation view thereof.

FIG. 7 is a front elevation view thereof; and,

FIG. 8 is a top plan view of the clamping tool shown in a position of use applied to a squeezable tube, shown in broken lines.

The subject matter delineated in broken lines illustrating environment forms no part of the claimed design.

1 Claim, 5 Drawing Sheets(56)
